Primary Examiner — T. Chase Nelson*Assistant Examiner* — Michelle E Wilson(74) *Attorney, Agent, or Firm* — Amanda T. Barry**CLAIM**

The ornamental design for a sanitary napkin, as shown and described.

DESCRIPTION

FIG. 1 is a perspective view of a sanitary napkin showing our new design;

FIG. 2 is a top view of a first embodiment of a sanitary napkin as shown in FIG. 1;

FIG. 3 is a bottom view of the sanitary napkin as shown in FIG. 1;

FIG. 4 is a left side view of the sanitary napkin as shown in FIG. 1;

FIG. 5 is a right side view of the sanitary napkin as shown in FIG. 1;

FIG. 6 is a front side view of the sanitary napkin as shown in FIG. 1; and,

FIG. 7 is a back side view of the sanitary napkin as shown in FIG. 1.

The broken lines depict portions of the sanitary napkin that form no part of the claimed design.
